Andrew Wilson.

UNITED STATES PATENT OFFICE.

JOHN J. McGUCKIN, OF BROOKLYN, NEW YORK, ASSIGNOR TO LOUIS SCHWAB, OF NEW YORK, N. Y., DOING BUSINESS UNDER NAME OF STEVENS & COMPANY.

BENCH BLOCK.

1,426,658.

Specification of Letters Patent. Patented Aug. 22, 1922.

Application filed March 16, 1921. Serial No. 452,739.

To all whom it may concern:

Be it known that I, JOHN J. McGUCKIN, a citizen of the United States, residing at Brooklyn, Kings County, New York, have 5 invented certain new and useful Improvements in Bench Blocks, of which the following is a specification.

My invention relates to bench blocks which are intended to be used by mechanics 10 in straightening, testing, and truing articles, and for other similar shop operations. My improvements are directed particularly to means whereby a single bench block is made to combine facilities for performing several 15 of the operations mentioned, in a more satisfactory and accurate manner than has been possible with the blocks heretofore in use.

In the drawings, Fig. 1 is a perspective view of a bench block embodying my improvements; Fig. 2 is a perspective view of the same reversed; Fig. 3 is a cross sectional view taken as on the lines 3, 3 of Fig. 2, and showing a bar, or similar article, resting 20 across the block; Fig. 4 is a view similar to Fig. 2, but with the highly polished plate 25 and its fastenings removed; and Fig. 5 is a detail of the one of the fastening elements of the block.

Similar parts are referred to by similar 30 reference numerals in all the figures.

The bench block 1 is provided with a leveled and, preferably, planed face 2, across which it is desirable to form a V groove 3, the use of which is well understood in the 35 art. The face 2 is intended for use in the rougher grades of work, and is therefore, not highly polished or finished. It is reinforced by a suitable flanged bridge work 4, 5, 6; and it is provided with a marginal flange 40 7, 7, the bearing corners 8, 8 of which are, preferably, provided with V grooves 9, 9.

In the flanged bridge work are provided 45 suitable anchor points, as the bosses 10, 10, which are shown as made integral with the bridge work, and as being tapered and screw threaded at 11, to receive screw threaded bolts 12, 12, which are passed through holes in a highly polished plate 13, which plate is secured to the bridge work by the bolts; 50 spring washers 14, or other suitable and yieldable packing being inserted between the plate and the bosses, and another washer or backing 15 being placed beneath the head of each bolt 12, so that the plate, while being 55 held firmly and securely, is somewhat

cushioned in its relation to the rest of the bench block, and is also susceptible of a slight vertical adjustment in relation thereto.

The plate is shown as so proportioned the V grooves 9, 9 lie outside of the marginal edges of the plate; so that an article, for instance a rod 16, when supported in the grooves, will lie free of the edge of the plate, and may be straightened, or otherwise manipulated, without coming in contact with the plate; while, at the same time, the edge of the plate may be referred to as a sighting base by comparison with which the rod or other article may be approximately trued.

The edge flanges 7 are shown as provided 70 with depressions 17, the surfaces of which are upon the same level as the upper face of the plate 13. So that if such an article as the rod 16 is laid from 17 to 17, across the plate 13, as shown in Fig. 3, if the rod 16 is 75 true, it will lie evenly upon the surfaces 17, 13, 17; and if there are any irregularities in its surface they may be detected by comparison with the plate 13, in the well known manner.

It will be seen, therefore, that in my improved bench block I secure not only a strong and approximately smooth surface 2, for use in the rougher kinds of work, but also a highly polished surface adapted for 85 use in connection with delicate and accurate work, as well as means associated with the highly polished surface for holding articles free from that surface, but in such a position that they may be referred thereto in the 90 process of truing them; and also means whereby such articles may be supported across the highly polished face of the plate in the process of accurately truing them by reference thereto. Besides this, the highly 95 polished plate is susceptible of sufficient adjustment to allow it to be accurately trued in reference to certain testing points on the frame work of the block; and is cushioned sufficiently to moderate the jars and shocks 100 which may be communicated to the face 2 of the plate when in use for comparatively rough work; so that the highly polished and comparatively thin plate 13 will not be injured by such shocks or jars; while the highly 105 polished plate is so disposed upon the frame work of the bench block that its surface, preferably, lies above the level of the supporting portions of the block when it is placed with the highly polished plate down,

80

110

being thus protected from abrasion or other injury which would be likely to result if the highly polished plate was laid flat, face downward, upon an ordinary work bench or 5 similar rough support.

It will be understood that details of construction may be modified, as by the use of mechanical equivalents and the like, without departing from the scope and spirit of my 10 invention as claimed.

Having thus described my invention, what I wish to secure by the Letters Patent of the 15 United States, is:—

1. A testing and truing bench block provided upon one side with a comparatively 20 roughly finished working face and upon its reverse side with a supplementary plate provided with a highly polished working face.

2. A testing and truing bench block provided upon one side with a comparatively 25 roughly finished working face and upon the reverse side with a supplementary plate 30 detachably attached thereto and provided with a highly polished working face.

3. A testing and truing bench block provided upon one side with a comparatively 35 roughly finished working face and upon the reverse side with a supplementary plate 40 adjustably attached thereto and provided with 45 a highly polished working face.

4. A testing and truing bench block provided with a face plate adjustably secured thereto at a plurality of points.

5. A bench block provided with a face plate adjustably secured thereto, and with 50 marginal elements extending beyond the plane of the face plate.

6. A bench block provided with a face plate adjustably secured thereto, and with marginal elements having work seats therein 55 and extending beyond the plane of the face plate.

7. In a bench block, the combination of a base having an integral, marginal flange and 60 integral reinforcing bridge work, and a face 55 plate adjustably attached to said bridge work.

8. In a bench block, the combination of a base having an integral, marginal flange and 65 integral, reinforcing bridge work, and a face 50 plate adjustably and detachably attached to said bridge work.

9. In a bench block, the combination of a base having an integral, marginal flange and 70 integral, reinforcing bridge work, a face 55 plate adjustably secured thereto, and shock absorbing means interposed between the bridge work and the face plate.

JOHN J. McGUCKIN.
